(57) **CLAIM**

The ornamental design for an interbody fusion device implant, as shown and described.

DESCRIPTION

FIG. 1 is a front perspective view of an interbody fusion device implant illustrating the design;

FIG. 2 is a rear perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

FIG. 8

UNITED STATES PATENT AND TRADEMARK OFFICE
CERTIFICATE OF CORRECTION

PATENT NO. : D620,110 S
APPLICATION NO. : 29/328826
DATED : July 20, 2010
INVENTOR(S) : Courtney et al.

Page 1 of 6

It is certified that error appears in the above-identified patent and that said Letters Patent is hereby corrected as shown below:

The Title page;

The Title page, showing the illustrative figure, should be deleted and substitute therefor the attached Title page.

Delete figs. 1-8 and substitute therefor the drawing sheets, consisting of figs. 1-8 as shown on the attached pages.

Signed and Sealed this
Twentieth Day of September, 2011

David J. Kappos
Director of the United States Patent and Trademark Office

(57) **CLAIM**

The ornamental design for an interbody fusion device implant, as shown and described.

DESCRIPTION

FIG. 1 is a front perspective view of an interbody fusion device implant illustrating the design;

FIG. 2 is a rear perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.
